**CONTAINER COVER FOR A COMBUSTION
ENGINE VAPOR INJECTOR**

Boyd E. Barefoot, 2532 SW. 63,
Oklahoma City, Okla. 73159

Filed Dec. 21, 1970, Ser. No. 26,600

Term of patent 14 years

Int. Cl. D8—03

U.S. Cl. D8—254

FIG. 1

FIG. 2

FIG. 1 is a perspective view of a container cover for a combustion engine vapor injector embodying my new design; and,

FIG. 2 is a perspective view of the container cover for a combustion engine vapor injector in an inverted position from that shown in FIG. 1.

I claim:

The ornamental design for a container cover for a combustion engine vapor injector, substantially as shown.
